(57) **CLAIM**

The ornamental design for a nursing manikin, as shown and described.

DESCRIPTION

FIG. 1 is a front, right and top perspective view of a nursing manikin, showing my design.

FIG. 2 is a rear, left and top perspective view thereof.

FIG. 3 is a rear, right and bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof; and,

FIG. 10 is another front, right and top perspective view of the nursing manikin of FIG. 1, shown in a secondary position with environment.

The broken lines immediately adjacent to the claim depict the bounds of the claimed design, while other broken lines are directed to environment of the nursing manikin that forms no part of the claimed design.
